(57) **CLAIM**

The ornamental design for a U-shaped desk as shown and described.

DESCRIPTION

FIG. 1 is a front perspective view of a U-shaped desk. FIG. 2 is a front view of the U-shaped desk of FIG. 1. FIG. 3 is a rear view of the U-shaped desk of FIG. 1. FIG. 4 is a right view of the U-shaped desk of FIG. 1. FIG. 5 is a left side view of the U-shaped desk of FIG. 1. FIG. 6 is a top view of the U-shaped desk of FIG. 1. FIG. 7 is a bottom view of the U-shaped desk of FIG. 1. FIG. 8 is a rear perspective view of the U-shaped desk of FIG. 1; and, FIG. 9 is an environmental front perspective view of the U-shaped desk of FIG. 1 with the desk legs in collapsed positions reducing the working height of the U-shaped desk. All broken lines seen in the drawings depict portions of the U-shaped desk that form no part of the claimed design.

1 Claim, 8 Drawing Sheets
